Specification for Design.

Patented Oct. 8, 1912.

Application filed August 23, 1911. Serial No. 645,660. Term of patent 7 years.

To all whom it may concern:

Be it known that I, LINDSLEY SCHEPMOES, a citizen of the United States, residing at Hasbrouck Heights, in the county of Bergen and State of New Jersey, have invented a new, original, and ornamental Design for Candelabra, of which the following is a specification.

The nature of my design is fully illustrated in the accompanying drawing, to which reference is made, and in which—

My design comprises a candelabrum having a base portion relatively long as compared with its width, spaced upright standards on the base surmounted and joined by a transverse bar provided with pendants symmetrically disposed thereon, having the contour and relative proportion of parts shown.

I claim:

The ornamental design for a candelabrum as shown and described.

LINDSLEY SCHEPMOES.
